[57] **CLAIM**

The ornamental design for an electrical component tray for a luminaire, substantially as shown and described.

DESCRIPTION

FIG. 1 is a perspective view of an electrical component tray for a luminaire showing my new design, taken from the top, one end and one side thereof;

FIG. 2 is a top, plan view of the electrical component tray of FIG. 1;

FIGS. 3 and 4 are opposite side elevational views of the electrical component tray of FIG. 1;

FIG. 5 is a bottom, plan view of the electrical component tray of FIG. 1; and

FIGS. 6 and 7 are opposite end, elevational views of the electrical component tray of FIG. 1.

FIG. 2

FIG. 3

FIG. 4

FIG. 5

FIG. 6
